(57) **CLAIM**

The ornamental design for a grater with collecting base, as shown and described.

DESCRIPTION

FIG. 1 is a perspective view of the grater with collecting base showing my new design.

FIG. 2 is a side view thereof.

FIG. 3 is another side view thereof.

FIG. 4 is a top view thereof.

FIG. 5 is a bottom view thereof.

FIG. 6 is another side view thereof.

FIG. 7 is another bottom view thereof.

FIG. 8 is an exploded perspective view thereof; and, FIG. 9 is a perspective view of grater portion contained within the base portion thereof.

The broken lines in the drawings illustrate portions of the grater with collecting base which form no part of the claimed design.
